In Germany July 7, 1937

3 Claims. (Cl. 250—27)

The present invention relates to cathode ray tubes and more particularly to electron lenses which control the direction of travel and focus of the electrons forming the beam.

It is known that on connecting a high-frequency alternating potential to a suitably constructed accelerating system in a cathode ray tube, charged particles may be given a velocity which is greater than that corresponding to the amplitude of the alternating potential. The fact is thereby used that the particles in the system possess periods of motion which are of the same order as the period of the alternating potential. Thus, a particle, for which exists at a given instant an accelerating field in the one field part and a retarding field in the other field part, may actually continuously be accelerated, because it reaches the second field part at a later time than the first field part. In the meantime, the direction of the alternating potential has been reversed, and the retarding field has become an accelerating field.

According to the invention, high-frequency alternating fields are used for the focusing effects of electron- or ion lenses. The lenses according to the invention differ from the known arrangements using electrical lenses operated by alternating potential in that, with these, the period of the alternating potential is of the order of the time of motion of the electrons in the lens, while with the known arrangements, where alternating potentials of network frequency have been used, the period is only a fraction of the time of motion of the electrons from the position of the object to the position of the picture.

Details of the invention are explained by the aid of the drawing in which Figs. 1 to 3 represent typical improved electron lenses together with a graphical explanation of their mode of operation and Fig. 4 is a diagrammatic representation of a cathode ray tube apparatus for usefully applying the invention.

Fig. 1 shows an immersion lens, which according to Fig. 1a consists of two co-axial hollow cylinders 10, which have different potentials with respect to ground or other fixed potential. The direction of the optical axis is indicated by z . Figs. 1b and 1c illustrate for two different conditions of operation the instantaneous variations of potential level which exist as one proceeds from left to right along the optical axis. Fig. 1b represents such variation for a retarding lens system and shows that the negative potential level increases along the optical axis. For an 55

accelerating lens the negative potential level decreases as shown in Fig. 1c.

The symbol I placed above the axis z in Fig. 1b indicates that the lens effect of the potential field to the left of the central plane of the lens is such as to produce divergence of the electron beam traversing the lens. The symbol O placed above the axis z to the right of the lens center line, on the other hand, indicates a converging effect of the lens system. In Fig. 1c the regions of convergence and divergence are reversed. It will be seen from the illustration, that in both lenses, i. e. the accelerating and the retarding lens, there are areas with divergent effect and areas with convergent effect. It will furthermore be seen that the divergent effect always appears in the area of high electron velocity, which has the result that the lens as a whole represents in both cases a convergent lens. These considerations made with respect to the immersion lens are true quite generally for any type of the short immersion or single lens. Only by using aperture stop lenses it is possible to make divergent lenses. But also when using aperture stop lenses, it is not possible to make chromatically corrected lens systems.

If now an immersion lens is operated with high-frequency alternating potential, the frequency and phase of which is so selected, that certain electrons pass through the first part of the immersion lens during the one-half wave and through the second part during the other half wave of the alternating potential, it is possible to obtain a pure convergent lens or a pure divergent lens. This fact is explained by the aid of Figs. 1d and 1e in the case of a pure divergent lens. Fig. 1d represents the variation of the form of the potential field as a given electron progresses through the field, the condition of the field being indicated for nine equally spaced positions of the electron. Fig. 1e represents the continuous variation of the applied alternating potential with electron position. Consider first an electron which at a certain instant is at the point signified by the Roman numeral I of Fig. 1d, and let the alternating potential assume the value of zero at this instant. Under these circumstances, the potential field is also of zero value at all points as indicated by the dash line associated with numeral I in Fig. 1d. Due to its starting velocity the electron reaches the point II at a time when the alternating potential has attained a positive value such that the potential field is of the character indicated by the dot-dash curve associated with numeral 2 in Fig. 1d.

Thus, in the area where the electron is that part of an immersion lens which corresponds to a divergent lens is formed. When the alternating potential obtains its maximum value, the electron is at the point III, so that now the most strongly curved potential curve 3 is formed. During the next quarter phase of the alternating potential, the electron passes through the points IV and V, during which the field is decreased according to the curves 4 and 5. When the electron passes now through the second part of the immersion lens, where there would be according to Fig. 1b a convergent effect, the alternating potential has according to Fig. 1e reversed its sign and has thus changed the second part of the immersion lens into an accelerating part. While the electron moves from V to IX, this accelerating field is according to the curves 5 to 9 built up and then decreased. Also in the second part of the lens, the electron is then made subject to a divergent effect.

By applying alternating potential, it is therefore possible to change the immersion lens into a pure divergent lens. Correspondingly, if the phase of the alternating potential is shifted about 180°, or the instant, at which the electron reaches the lens, is shifted about 180° of this potential, the immersion lens may be changed into a convergent lens of amplified effect. But the possibility of making a divergent lens is of special importance, since a divergent lens similar to the optical divergent lens was hitherto not known in electron-optics, so that it was also not possible to construct an achromatic lens arrangement.

The idea of operation with alternating potential is, of course, not limited to an immersion lens. Figs. 2 and 3 respectively represent as further cases a so-called single lens (Fig. 2a') consisting of three electrodes 12, 13 and 14 and an immersion objective lens (Fig. 3a'') consisting of a cathode 15 and two cylinders 16 and 17. Figs. 2b' and 3b'' illustrate for these two cases the static potential field distribution at a given instant. Figs. 2d' and 3d'' respectively indicate the variations in field form which occur for the two constructions under consideration as a chosen electron proceeds through the lens space. In connection with the latter figures the assumed electron position is indicated by Roman numerals and the corresponding field form is indicated for each position by a curve which bears an Arabic numeral corresponding to the Roman numeral associated with such position. With the field conditions indicated, a divergent lens action is obtained. Figs. 2e' and 3e'' show, for the two lens constructions to which they respectively pertain, the nature of the variation of potential magnitude with electron position. These curves are based on the assumption of an alternating potential which varies sinusoidally with time, but the plotting of the curves is not against time but against space, the transformation having been made by taking into consideration the known velocity of the electrons. While in Fig. 2e' the distortion of the resultant curve from the sinusoidal is not important it is quite marked in Fig. 3e''.

In the above, and especially in Figs. 1d, 2d' and 3d'', the effect of an electric lens operated with alternating potential has been described by reference to curves illustrating how the potential field varies from time to time. This representation is somewhat incomplete in that for the sake of clearness the potential field variation has been

described as discontinuous. In reality, of course, the form of the potential field (i. e. the electron lens field) varies continuously as the electrons progress from point to point.

With alternating fields, the signification of the potential is not the same as with static fields. It is more suitable in this case not to consider the concept of potential and to work with the effect of force. In the static case, the force acting on an electron in the vicinity of the axis is in the case of a potential $V=U(z)$: $E=-U''r$, where the primes mean derivatives with respect to z and where r is the distance of the electron from the axis. U may, for example, be the potential, illustrated by Fig. 1b or 1c, of the immersion lens. If now the immersion lens is operated with alternating potential, the potential is of the form $V=U(z) \sin ft$, and the force is therefore $E=U''r \sin ft$, as will be understood from the paper by Brüche and Recknagel in the "Zeitschrift für technische Physik," vol. 17, p. 126 ff. (1936), particularly from the note 12 on page 132. Constant proportionality factors have here been neglected. While in the purely static case, the type of lens effect, namely the sign of E , is solely determined by the sign of U'' , with the lens operated by alternating potential there has still to be added the sign of the sine-factor variable with time. Furthermore, the magnitude of the force, i. e. the magnitude of the convergent or divergent effect existing at the time, is influenced by the variable magnitude of this factor.

The lenses operated with alternating potential may, of course, be used just as well for positive particles as for electrons. In order to obtain the same effect, only the potentials in the lens electrodes have to be reversed with respect to the potentials selected for the electrons. Also, magnetic lenses may be operated in the same manner. It is of special advantage to use two coils connected in series. At a certain strength of the current flowing in the same direction in both coils, it may then be achieved that the picture rotation effected by the coils is 180°, so that the picture appears upright. But if the same coils are operated with alternating current, in such a manner that the electron is subjected to oppositely directed magnetic fields, the picture is not rotated. By optional operation of these coils with direct- or alternating current, an upright or a reversed picture may thus be obtained as desired.

Hitherto, the case has been considered that a sinusoidal potential or a sinusoidal current serves to operate the lenses. It is, of course, possible to use potentials of different wave shape, such as rectangular or triangular, obtained in a well-known manner. The use of rectangular potentials or currents has the advantage that the maximum possible lens effect obtainable with a given field arrangement is achieved. If the immersion lens discussed in Fig. 1 were operated by a rectangular potential, the potential field would have the shape indicated at 3 in Fig. 1d while the electrons pass through the first part of the lens, and in the second part of the lens would have the shape illustrated by 7. The same thing is true on using magnetic lenses, since also in this case, the whole refractive power of the first lens, and then the whole refractive power of the second lens, would become effective.

It is, of course, possible to combine the lenses operated by alternating potential according to the invention with static electric or magnetic lenses. This is particularly of advantage for the

manufacture of a chromatically corrected lens arrangement, since the convergent lens may be produced by a known static lens, while the divergent lens necessary for the correction is produced by an alternating potential lens. On using several lenses operated by alternating potential or alternating current, it is suitable to use a single voltage or current source. In the leads to the single lenses, devices may be provided which influence the phase of the potential or alter its shape. It is, for example, possible to use a potential source which produces a sinusoidal potential, and to operate only one of the lenses with this sinusoidal potential, while another lens is operated by aid of a rectangular potential. The form obtained from the first-mentioned potential, as well as the magnitude of the potentials may be different for the different lenses.

As the desired effect of a lens occurs only at certain ranges of the electric phase, care has to be taken, that with image devices using alternating potential lenses, the charged particles enter the lens only in these phases (i. e. during periods which include an instant of potential reversal). This might be achieved by the use of an anode positioned near the cathode and having an accelerating potential taken from the same alternating current source as the lens potentials. Also, devices may be inserted in the leads which deliver the alternating potential in order to alter the phase shape or magnitude of the potential, or several of these characteristics at the same time.

In Fig. 4 there is illustrated diagrammatically a complete cathode ray tube apparatus for usefully applying the invention. This comprises an elongated envelope having a tubular shaft portion 20 and an enlarged bulbous portion 21. At one end of the envelope there is provided an electron source comprising the combination of a cathode 23, a first accelerating electrode 24 and a second accelerating electrode 25. A battery 27 serves to impress an accelerating potential between the cathode 23 and the electrode 25. At the end of the envelope remove from the electron source there may be provided a fluorescent screen on the wall surface 28, as is conventional in tubes of this character.

Between the electron source and the wall surface 28 there is provided an electron lens system of the type illustrated in Fig. 3 hereof. This comprises a first cylindrical electrode 30 which is arranged in partially telescoped relation with a second generally cylindrical electrode 31 consisting, for example, of a conductive coating applied to the interior surface of the envelope. These elements are supplied with alternating potential from a source which is conventionally represented as a transformer 33. It is assumed that the frequency of the source 33 is sufficiently high so that the time required for potential reversal is of the order of magnitude of the time taken by electrons in passing through the lens field created between the cylinders 30 and 31. As has been previously explained, this expedient assures that a given electrode shall be subjected to the same directional effect throughout the entire region of influence of the lens system. In order that electrons may enter the lens system only when the phase of the potential applied thereto is favorable to the production of the desired focusing

effect, use may be made of the accelerating electrode 24. In this connection, the electrode may be connected to the source 33 which supplies potential to the lens system and may be energized thereby in such fashion that it permits electron current to flow only at intervals which are calculated to bring the electrons into the lens system in the proper phase relationship. Known biasing means such as a battery 35 may be used to assist in the performance of this function.

As a result of the means described in the foregoing, the electrons which traverse the lens system may be focused in a desired fashion upon the wall surface 28. If desired, the apparatus may include magnetic or other means, illustrated diagrammatically at 37, for producing a cyclical deflection of the thus focused beam.

What I claim as new and desire to secure by Letters Patent of the United States is:

1. In a cathode ray tube, means for producing a beam of electrons and an electron lens system which possesses utility mainly by virtue of its ability to control the lateral dimensions of the beam, said lens system comprising a pair of mutually spaced apertured electrodes arranged to be successively traversed by the beam, means for applying a potential between the electrodes and for periodically reversing such potential to produce an alternating lens field between said electrodes, and means for causing electrons to pass through said lens field only during periods which include an instant of potential reversal.

2. In a cathode ray tube, the combination which includes means for producing a beam of electrons and an electron lens system which possesses utility mainly by virtue of its ability to control the lateral dimensions of the beam, said lens system comprising a pair of partially telescoped conducting cylinders arranged to be successively traversed by the beam, means for impressing a potential between the cylinders and for reversing such potential with a periodicity which is of the order of magnitude of the time taken by the electrons in passing through the lens system to produce an alternating lens field between said cylinders, and means for causing electrons to pass through said lens field only during periods which include an instant of potential reversal, whereby electrons are subjected to the same directional effect throughout the entire region of influence of the lens system.

3. In apparatus which includes means for producing an electron beam and in which it is necessary for the proper functioning of the apparatus to exert a constant focusing effect on the various components of the beam, the combination of an electron lens system in the path of said beam for producing the said required focusing of the beam by exerting transverse refractive forces on the various components of the beam, a source of alternating potential for energizing the said lens system to provide an alternating lens field, the operating frequency of the said source being sufficiently high to assure the reversal of the potential in a period which is of the order of magnitude of the time taken by the electrons in passing through the lens field, and means for causing the electrons to pass through said lens field only during periods which include an instant of potential reversal.

ERNST BRÜCHE.
